CLAIM

The ornamental design for a case for mobile telephone, as shown and described.

DESCRIPTION

FIG. 1 is a perspective view of a case for mobile telephone showing my new design;

FIG. 2 is a front elevational view thereof;

FIG. 3 is a top plan view thereof;

FIG. 4 is a left side elevational view thereof;

FIG. 5 is a rear elevational view thereof;

FIG. 6 is a right side view thereof; and,

FIG. 7 is a bottom plan view thereof.

The broken lines in the drawing figures form no part of the claimed design, and they depict portions of the case for mobile telephone that form no part of the claimed design.
